SAMUEL S. AMDURSKY, OF ROCHESTER, NEW YORK, ASSIGNOR TO TAYLOR INSTRUMENT COMPANIES, OF ROCHESTER, NEW YORK, A CORPORATION OF NEW YORK

MANOMETER

Application filed October 25, 1930. Serial No. 491,146.

The invention relates to manometers of the type for measuring the pressure conditions of the circulatory system and more in particular to that form of manometer where 5 in the operating pressure is balanced against a column of liquid, usually mercury.

One of the great drawbacks of this form of measuring device is the setting up of oscillations of the mercury column due to 10 the rhythmical variations of the pulse wave, which oscillations make it difficult to read the values of the static pressure applied for producing the constricting effect upon the artery. The systolic pressure and the diastolic pres- 15 sure are determined from the characteristic sounds observed by means of the stethoscope during the gradual release of the pressure from the constricting cuff and it is of the utmost importance that the pressure indicated 20 by the mercury column is the true pressure causing the constrictive effect. Since it is impossible to avoid the rhythmic reactions of the blood stream upon the pressure-respon- 25 sive walls of the constricting cuff and upon the pressure fluid therein, it is necessary to find the true effective pressure values at which the characteristic sounds are observed.

It is impossible for even the keenest ob- 30 server to correctly read the true value be- tween the upper and the lower level of the oscillating mercury column. The amplitudes of the oscillations vary in proportion to the pulse pressure, the pulse rate and the height of the mercury column, and at times 35 may be 15 m. m. or more and the difficulty of reading is considerably increased by the changing form of the meniscus.

The amplitudes are the larger the more the pulse rate approaches the natural period 40 of oscillation of the mercury column, which oscillation is a damped simple harmonic motion.

The undesirable character of these oscillations was recognized for many years and 45 attempts were made to eliminate them or at least materially reduce them. Heretofore, the only apparent remedy devised was a resistance to the flow of the mercury from the cistern to the tube or to the flow of air above 50 the column out of the tube or to the flow of

the pressure medium from the cuff into the cistern. While these constricting measures effect a damping out of the oscillations, they accomplish the object only due to a time lag introduced by the frictional resistance. Al- 55 though investigations in this field have not been completed and the technique is too intricate to dispose of the different questions in a short time, the evidence clearly indicates that for the usual practice of making the ob- 60 servations on a decreasing cuff pressure, the readings of the mercury column are mate- rially higher than the true pressure in the cuff would call for. This error in the read- 65 ing varies in proportion to the rate at which the operator allows the air to leak out of the system and also in proportion to the height of the column when the reading is taken.

Aside from the error due to the lag, in general, the difficulty is thus aggravated by 70 these two variable factors which do not admit of standardization or application of calibration constants.

The object of the present invention is a mercurial manometer of the class referred 75 to wherein the pulsations tending to main- tain the mercury column in an oscillating condition are damped out or dissipated without causing any time lag or any ap- 80 preciable time lag in the establishment of a true balance between the weight of the mer- 85 cury column and the static pressure in the cuff.

Expressed in different form, it is the object 90 of the invention to provide a mercury ma- nometer wherein at the time of a stetho- scopic indication the true corresponding value of the pressure in the bag may be instantaneously read from the position of the mer- 95 cury column.

For a full understanding of the invention, the principle of operation on which it is based and its advantages, reference is made to the accompanying drawing wherein

Fig. 1 is a front view of one arrangement 95 embodying the invention;

Fig. 2 is a sectional view of another con- struction embodying the invention;

Fig. 3 is a section on line 3—3, Fig. 2; and

Fig. 4 is a sectional view of what I now 100

consider as a preferred form of the invention.

In Fig. 1, 1 represents a part of the cuff or pneumatic armlet generally placed over the upper arm and held in place by means of a sleeve of inelastic material. There are two connections 2a and 2b to the cuff, one of which carries the usual hand bulb 2 and the other of which is in fluid connection with the cistern 3 which acts as the pressure chamber for the measuring tube 4, being connected thereto by the bent tube 5. The tube 4, bent tube 5 and cistern are mounted upon a suitable standard 8.

15 The structure thus far described represents generally the usual form of a mercury sphygmomanometer.

20 The salient feature of the invention is the interposition between the cuff 1 and the cistern 3 of a means for damping out vibrations or oscillations transmitted from the cuff toward the tube 4. A very effective means to this end is a vessel 6 which is in fluid connection with the cuff, on the one hand, and with the cistern 3, on the other hand.

25 The operation is, of course, generally the same as in all usual forms of apparatus of this type. The cuff is pumped up and part 30 of the air flows into the cistern 3 and forces an amount of mercury into the tube corresponding to the pressure in the cuff 1.

35 One of the characteristic features of the invention is the absence of any form of means tending to impede or retard an equalization of pressures between the pressure medium in the cuff, on the one hand, and the pressure of the mercury column, on the other hand. The fluid connection between the cuff 40 and the tube is free of constricting means and the upper end of the tube is entirely open during measurements or if there is a closure for preventing the escape of mercury, such closure is of such construction as 45 not to materially affect the flow of air into and out of the tube when the mercury column is made to rise or fall.

50 It is the usual practice to pump air into the cuff until the pressure in the system is greater than the systolic pressure expected in the patient. Then the pressure is gradually decreased by allowing air to escape through the leak valve 7, until the physician hears the characteristic sound indicating the 55 systolic pressure. When he hears this sound, he notes the reading of the mercury column and, allowing the air to continuously escape, he follows the column down until he hears the sounds characteristic of the diastolic pressure when he takes another reading.

60 In the invention described, the mercury column is always in equilibrium with the pressure in the cuff. This effect is obtained, 65 in the first instance, by the omission of re-

strictions in the flow path of the air and the mercury, and secondly, by the damping out of all the vibrations which usually, in the absence of constricting means, set the mercury column in motion and maintain it in motion. The waves set up by the pulse beat are leveled out in the body of air in the vessel 6, so that the pressure at the outlet of the vessel 6 and in the reservoir manifests itself solely as static pressure.

70 Naturally, the larger the body of air in the vessel i. e. the larger the vessel, the greater is the leveling out or damping effect. However, I have found that a relatively small volume, a volume several times larger than the average volume of the cuff, i. e. of the order of about $\frac{1}{2}$ to 1 liter, gives perfect satisfaction.

75 Having reference to Figs. 2 and 3, the vessel 10 for damping out the oscillations is mounted on the inside of a cover 11a of the casing 11 containing the apparatus. The cistern 12 is disposed within the vessel 10 and is in fluid connection with the latter through a tube 13 which is so disposed that the mercury cannot escape when the cistern is in a horizontal position. The tube 14 together with the scale plate 16 is supported directly on the wall of the vessel 10. A nipple 17, preferably at the bottom of the vessel 10, adjacent to the bent tube 15 serves to make fluid connection to the interior of the vessel from the cuff. Arms 18 pivotally interconnecting the lower part and the upper part of the casing 11 are provided for swinging the latter and the manometer as a unit into an upright position, as indicated in Fig. 2 in dotted lines.

80 The form of apparatus shown in Fig. 4 is a reduction of the invention to its simplest form. The damping vessel and the cistern or reservoir are defined by a single vessel 20 the lower portion 20a of which is preferably funnel-shaped to constitute the cistern from which a bent tube 21 makes fluid connection to the manometer tube 22 on the opposite side of the standard 23. A connection 24 preferably extending through the bottom of the vessel 20 to the top thereof, serves for making fluid connection to the cuff. The standard 23 may be supported similarly to the cover 11a, as a part of a casing or in any other desired manner.

85 The manometer tube may be closed at its top in any suitable manner provided the closure does not introduce a material resistance to the flow of air into and out of the tube. For the purposes of illustration, I have indicated an enlargement 25 of the tube in which by means of a perforated screw plug 25a, a septum (not shown) may be confined, which septum allows air to freely pass, but forms a barrier to the flow of the mercury.

90 In the foregoing I have described the essential features of my invention. It is un-

derstood that there are many forms in which the invention may find expression.

I claim:

1. In a manometer of the character described, the combination with a cuff, a pressure chamber, a measuring tube connected to the pressure chamber and a liquid in the pressure chamber and the tube, of a closed vessel in fluid connection with the cuff and the pressure chamber, said vessel having a volume capacity such as to materially damp out pulsating waves coming from the cuff.

2. In a manometer of the character described, the combination of a cuff, a pressure chamber, a fluid connection between the cuff and the pressure chamber, including a closed vessel having a volume capacity in excess of the volume of the cuff and a measuring tube connected with the pressure chamber, containing a measuring liquid.

3. In a manometer of the character described, a measuring tube, a pressure chamber in fluid connection with the tube, a closed vessel having an inlet therein for communication with a cuff, a fluid connection between the said vessel and the pressure chamber, and a standard for supporting the said vessel, the tube and the pressure chamber in operative relation.

4. In a manometer of the character described, a standard, a measuring tube, a pressure chamber and an air chamber in fluid connection therewith mounted as a unit on the standard, a connection between the tube and the pressure chamber and a cuff in fluid connection with the air chamber.

5. In a manometer of the character described, a measuring tube, a pressure chamber, a connection between the latter and the tube, an air chamber above the pressure chamber, forming an upward extension of the latter, a cuff in fluid connection with the air chamber, and a standard for supporting the said parts in operative relation.

6. In a manometer of the character described, the combination of a cuff, a measuring tube and a fluid connection between the cuff and the tube, including an air chamber having a volume capacity of such size as to substantially damp out pulsating waves set up in the cuff by the pulse beat.

7. In a manometer of the character described, the combination of a cuff, a measuring tube and a fluid connection between the cuff and the tube, including an air chamber having a volume capacity greater than the volume capacity of the cuff.

8. In a manometer of the character described, a standard, a vessel mounted on the standard, a measuring tube in fluid connection with the said vessel at the bottom thereof and disposed in substantially parallel co-extensive relation to the vessel, the vessel including at its bottom a part forming a pres-

sure chamber for the manometer liquid and above the pressure chamber an air space several times larger than the space of the pressure chamber.

9. In a manometer of the character described, the combination of a measuring tube, a vessel defining at its bottom a cistern for the measuring liquid and above the cistern an air space several times larger than the space of the cistern, a standard for the support of the vessel and the tube, a connection between the tube and the bottom of the said vessel, and a cuff in fluid connection with the air space of the vessel.

In testimony whereof I affix my signature.

SAMUEL S. AMDURSKY.
